(57) **CLAIM**

The ornamental design for an electric vehicle charger as shown and described.

DESCRIPTION

FIG. 1 is a front view of an electric vehicle charger;

FIG. 2 is a right side view thereof;

FIG. 3 is a back view thereof;

FIG. 4 is a left side view thereof;

FIG. 5 is a top, front, left perspective view thereof;

FIG. 6 is a top, front, right perspective view thereof;

FIG. 7 is a bottom, front, right perspective view thereof;

FIG. 8 is a bottom view thereof; and,

FIG. 9 is a top view thereof.

The ornamental design which is claimed is shown in solid lines in the drawings. The broken lines of equal length dashes in the drawings are for illustrative purposes and form no part of the claimed design.

1 Claim, 9 Drawing Sheets
